United States Patent Office.

JEROME FASSLER, OF SPRINGFIELD, OHIO.

Letters Patent No. 95,334, dated September 28, 1869.

IMPROVED BLANK FOR HARVESTER GUARD-FINGER.

The Schedule referred to in these Letters Patent and making part of the same.

To all whom it may concern:

Be it known that I, JEROME FASSLER, of Springfield, in the county of Clark, and State of Ohio, have invented a new and useful Improvement in the Manufacture of Harvester Guard-Fingers; and I do hereby declare the following to be a full, clear, and exact description of the same, reference being had to the accompanying drawings, in which—

Figure 1 represents a bar of metal with inscribed lines, showing the manner in which said bar is divided into blanks.

Figures 2, 3, 4, and 5, represent the blank during different stages of its manufacture into a guard-finger.

In manufacturing small articles, the great desideratum is to reduce the number of operations to the lowest number, and thereby to reduce the number of times each article must be handled during the process of its construction.

This is the object of the present invention, in connection, also, with the perfection and uniformity of the results attained.

Before the blank is presented to the dies, it should present, roughly, the form in which it is finally to be fashioned; and it has hitherto been customary, in the manufacture of guard-fingers, to produce the rough

blanks by hand-forging. This process involved a large amount of labor, which I dispense with, by procuring bars of suitable metal, of one and three-fourths by one inch cross-section, and by means of a powerful shearing-apparatus, cutting said bar into blanks, as represented in the lines of fig. 1.

No material is wasted in the cutting, except a small piece at either end of the bar.

The subsequent operations necessary to the formation of guard-fingers from the above-described blanks are fully set forth in the specification forming a part of my application for Letters Patent, filed of even date herewith, for machinery for manufacturing harvester guard-fingers.

Having now described my invention,

What I claim as new, is—

Shearing or punching blanks from solid plates or bars of iron or steel, substantially as shown in fig. 1, whereby the forging or forming of harvester guard-fingers is greatly facilitated in their manufacture, as herein set forth.

JEROME FASSLER.
